MAGNETIC CHARACTER PRINTING HEAD
 John C. Sims, Jr., Sudbury, Mass., assignor to Sperry
 Rand Corporation, New York, N.Y., a corporation
 of Delaware

Filed Sept. 15, 1965, Ser. No. 487,418
 7 Claims. (Cl. 346—74)

This present invention relates to an electromagnetic transducer useful in producing original typographical latent magnetic images.

In many cases it is desired to create typographical latent images which are not to be reproduced from pre-existing typographical originals, but which are to be translated from coded electric signals transmitted to a printer either from some remote point or from computing and business machines as the result of their manipulations and computations.

Accordingly, it is a primary object of this invention to provide an improved type of magnetic transducer or head structure capable of instantaneously recording the complete magnetic images of whole characters.

Further objects of the invention will become apparent from the following specification in conjunction with the accompanying figures in which:

In the drawings:

FIGURE 1 is a perspective view of an electromagnetic recording head in accordance with the invention;

FIGURE 2 is a perspective view illustrating elements of the recording head;

FIGURE 3 is an enlarged front view of the recording head shown in FIGURE 1 and illustrating the magnetic image array of one character;

FIGURE 4 is a fragmentary perspective view illustrating a modified form of the invention; and

FIGURE 5 is a fragmentary end view showing a portion of the printing cylinder used with the head.

Now with attention to the details of the various figures of drawings, it is seen that the transducer or head 10 comprises a plurality of comb-like members 12 each of high magnetic permeability, which might be made, for example, of soft iron, or the well known alloys such as those sold under the trademark "Hypersil" or "Permalloy." Each member 12 is provided along one edge with a plurality of tines 14 having gaps or notches 16 therebetween. For the purpose of illustration, and as a matter of preference, fifteen gaps are shown (FIGURE 3).

A plurality of the comb members 12, twenty in this case, are arranged in a stack with a slight space 18 between each pair. While other arrangements may be utilized, it is preferred to stack them in a box-like frame 20 with their opposite ends received in grooves 22 formed in the inner faces of the opposite side walls 24 and 26, and preferably with the tines and notches vertically aligned. When used with a drum 28, as seen in FIGURE 5, the front face of the head is curved complementary to the curvature of the drum and closely spaced therewith. The large number of gaps or notches produces better character definition, but more or less may be used as the occasion demands.

In this preferred form of the invention, a separate wire 29 is threaded through appropriate notches 16 in the shape of and for each letter of character to be printed. By way of example, to form the letter B a wire is threaded through the gaps 16 identified on FIGURE 3 by the circles 30 leaving the terminals 32 for connection with a suitable pulse source, such as a computer 33. It has been found that the use of a No. 36 wire to form each image and a twenty ampere pulse for one to five microseconds is quite satisfactory.

As indicated at 34 on FIGURE 2, connection of the

terminals 32 with such a pulse, effects a flow of magnetic flux across the ends of the gaps 16 traversed by the wire forming the particular character. In the case of the letter B as seen in FIGURE 3, it would be at those gaps in the circles 30 defining the letter in this figure. In accordance with the method disclosed in the Eckert et al. Patent No. 3,012,232, corresponding spots on the drum or printing cylinder 28 are magnetized by this flux. These spots are then developed by subsequent exposure to a suitable magnetic ink, usually in powder form, which is transferred from the drum to a sheet or web of paper, or other suitable printing medium, thus to print visible characters. Printing, of course, could take place directly upon a magnetic sheet or web, in which case the head face may be planar.

Instead of individual heads, such as shown in FIGURE 1, at each print position in a line of characters, the transducers for all printing positions may be in one unitary construction, as shown in FIGURE 4. In this form the combs 12 are of a length to extend across all printing positions, but with the individual character forming wires utilizing only those gaps sufficient to define any one of the characters to be printed at each position. This is particularly advantageous in that one wire may be threaded 25 throughout the length of the transducer to form a complete one line message, or for underlining up to a whole line of printing. Spacers may be provided between the combs at intervals along their lengths to hold the combs aligned.

30 In a modified form of the invention, instead of the single wire to form the characters, the base portions 36 of the members 12 in the areas corresponding to the respective gaps 16 are wound with separate energizing coils 38. While a coil may be provided at each of the gaps, 35 it will be obvious that it is more economical to provide them only at those gaps used in the formation of the characters to be printed.

In this case, each of the members 12, is similar to the transducer shown in FIGURE 1 of the above mentioned 40 Patent No. 3,012,232.

Preselected leads 40 from the ends of separate energizing coils 38 of each member are connected in series, as indicated by the broken lines 42 in FIGURE 2 and according to the characters to be printed, each head, as mentioned above, contains all of the characters.

By way of example, to form the letter B, all of the coils 38 at the gaps identified by the circles 30 on FIGURE 3 are series connected in a single circuit with the terminals 32. Similarly, the coils 38 are interconnected in series circuit in each head to form all other characters of a font. Obviously some coils will be used for more than one character or image. The number of turns per coil and the electric current required is dependent upon the material used in the printing cylinder or drum 28 (FIGURE 5) and the flux density required for proper magnetization on the surface of the drum in accordance with the printing method disclosed in the above identified patent.

60 The embodiments of the invention in which an exclusive property or privilege is claimed are defined as follows:

1. A magnetic transducer for instantaneously recording magnetic images or characters on a magnetic surface, comprising:

(A) a plurality of comb-like elements of high magnetic permeability, each having alternate tines and notches along one edge;

(B) means for holding said comb-like elements in stacked relation, one over the other with the tines and notches facing in the same direction;

(C) electrically conductive means threaded through certain of the notches in the shape of a character or image to be recorded; and

(D) means for connecting the said electrically conductive means to a pulse of electrical energy thereby momentarily to induce a flow of magnetic flux across the ends of each notch traversed by said pulsed electrically conductive means, whereby the character or image formed by the electrically conductive means may be magnetically recorded on a closely spaced magnetic surface.

2. A magnetic transducer according to claim 1 wherein:

(A) the tines and notches of the comb-like elements are vertically aligned.

3. A construction according to claim 1 wherein:

(A) the holding means comprises a rectangular frame having side walls, the inner surfaces of which are notched to receive the opposite ends of the comb-like elements.

4. A magnetic transducer according to claim 1, wherein:

(A) the electrically conductive means is a wire.

5. A transducer in accordance with claim 1, wherein:

(A) a plurality of electrically conductive means is threaded through the notches of said comb-like elements one upon another in different paths thus to form a plurality of characters or images for selective connection to the pulse source, whereby the one transducer may be used successively to record the same or different characters or images.

6. A magnetic transducer according to claim 1, wherein:

(A) said comb-like elements are elongated to accommodate a plurality of characters or images formed by individual electrically conductive means threaded

10

15

20

35

through said notches in side by side relation whereby a whole line of characters or images may be recorded simultaneously.

7. A magnetic transducer for instantaneously recording magnetic images or characters on a magnetic surface, comprising:

(A) a plurality of similar comb-like elements of high magnetic permeability each having alternate tines and notches along one edge;

(B) frame means for holding said comb-like elements in stacked relation slightly spaced one over the other with the tines and notches facing in the same direction and vertically aligned;

(C) individual electrically conductive wires threaded through certain of the notches of each wire in the shape of a character or image to be recorded; and

(D) means for selectively connecting each of the said wires to a pulse of electrical energy thereby momentarily to induce a flow of magnetic flux across the end of each notch traversed by said pulsed wire, whereby the character or image formed by the selected wire may be magnetically recorded on a closely spaced magnetic surface.
